UNITED STATES PATENT OFFICE.

JOSEPH LANE, OF DANVILLE, ILLINOIS.

FEATHERING PADDLE-WHEEL.

SPECIFICATION forming part of Letters Patent No. 274,345, dated March 20, 1883.

Application filed June 24, 1882. (No model.)

To all whom it may concern:

Be it known that I, JOSEPH LANE, of Danville, in the county of Vermilion and State of Illinois, have invented a new and useful Improvement in Paddle-Wheels, of which the following is a full, clear, and exact description.

The object of my invention is to provide for feathering the buckets or paddles of paddle-wheels, in order that they shall enter and leave the water edgewise.

To that end my invention consists in buckets or paddles sustained upon arms that are fitted for oscillation in a wheel of nearly the ordinary construction, and in combination therewith locks for preventing any movement of the buckets except at the proper time, all as hereinafter described and claimed.

Reference is to be had to the accompanying drawings, forming a part of this specification, in which similar letters of reference indicate corresponding parts in both the figures.

Figure 1 is a sectional side view of a paddle-wheel of my improved construction, a portion being broken away. Fig. 2 is a transverse section of the same.

A is the shaft; B B, the hubs, and D the arms of the wheel, fitted rigidly in the hubs B, and provided at their outer ends with two concentric rims, C C. d d are the oscillating arms, carrying the buckets or paddles E. These arms d are pivoted at about their mid-length in or to the outer rim C, and their inner ends extend into slots or mortises formed or provided in the inner rim C. By this construction the arms d are free to oscillate the distance regulated by the length of the slot in the inner rim.

The locking devices consist of cross-bars F, that extend transversely of the wheel at the inner surface of the inner rim C, and provided with blocks b b, that enter the slots or mortises of the rim. These bars F are hung upon the ends of arms e, that extend from the hubs B, to which they are held by suitable guides, f, and are provided with lugs or projections g, that take into the groove of cams H, that are attached upon the faces of the supports or bearings of the shaft A. The grooves of the cams H are so shaped that the cross-bars F are projected, and the blocks b thereon are moved into position for locking the arms d before the paddles enter the water, and while in the water until they reach their lowest

point, at which time the cams act to raise the cross-bars F, thereby permitting the arms d to swing and the buckets to assume the proper angle for leaving the water edgewise. During their upward movement the locks are drawn outward, thereby leaving the buckets free to fall on either side, which they will do by their own gravity, until they commence to move downward at the other side, when the locks are again projected.

Rubber bumpers h are placed at each end of the slots in the inner rim C to relieve the shock of contact by the arms d, and to prevent jarring and noise.

It will be observed that from each of the radial arms which connect the hub with the rims are two branches or braces on opposite sides. These extend with their outer ends to the rim-slots in which the ends of the arms d oscillate, and thus form abutments to take the end-thrust or upward strain which would otherwise come entirely upon the pivots of arms d.

The advantages of this construction are as follows: The oscillating paddle-arms can readily be applied to any paddle-wheel of ordinary construction by the feathering movement of the paddles; the power that is usually lost by the buckets entering and leaving the water sidewise is saved; the paddle-arms will work equally well backward or forward; the device for operating the locks being placed at the hub of the wheel, but little power is required for their operation.

The whole construction of the wheel is durable in every part, and it can be made of wood or iron, or of both combined, as may be desired.

Having thus described my invention, I claim as new and desire to secure by Letters Patent—

1. In a paddle-wheel, the combination, with the hubs B B, having fixed arms D and two concentric rims, C C, of the oscillating arms d, pivoted at the middle to the outer rim C, having inner ends extending into slots of the inner rim C, and carrying the buckets E, whereby the oscillation of the arms d may be regulated, as described.

2. The combination, with a paddle-wheel provided with oscillating arms d, a slotted rim, C, concentric with an outer rim, and the blocks b, arranged in mortises of said rim, of the bars F, hung upon hub-arms e by guides f, and provided with lugs g, and the grooved cams H,

arranged on supports or bearings of the shaft A, said cam-grooves being shaped to project the cross-bars, and thus move the blocks into position for locking the arms d, as described.

5. 3. The combination, with a paddle-wheel, of oscillating paddles, locking-frames e F for locking these paddles in position, the lugs g at the upper ends of the locking-frames, and the cam-plates H, into the groove or slot of which the lugs g pass, substantially as herein shown and described, and for the purpose set forth.

10. 4. The combination, with a paddle-wheel, of the arms d, pivoted in the outer rim C, the paddles E, attached to these arms, the locking-frames e F, the lugs g, the cam-plates H, and the guide-plates f on the hubs, substantially as herein shown and described, and for the purpose set forth.

15. 5. The combination, with a paddle-wheel, of

the oscillating arms d, pivoted in the outer rim C and passing into slots or mortises in the inner rim C, the paddles E, attached to the arms d, the blocks b, the frames e F, to which these blocks b are attached, the lugs g, and the cam-plates H, substantially as herein shown 20 and described, and for the purpose set forth.

6. The combination, with a paddle-wheel, of the oscillating arms d, pivoted in the outer rim C, passing into slots in the inner rim C, the cushions or pads h at the ends of this slot, the 25 paddles E, attached to the arms d, and the locking-frames e F, substantially as herein shown and described, and for the purpose set forth.

JOSEPH LANE.
